UNITED STATES PATENT OFFICE.

GEORGE C. FATSCHER AND CLARENCE E. BILLINGS, OF NEW HAVEN, CONNECTICUT,
ASSIGNORS TO THE NEW HAVEN SAND-BLAST COMPANY, OF NEW HAVEN, CON-
NECTICUT, A CORPORATION OF CONNECTICUT.

SAND-BLAST MACHINE.

Application filed March 26, 1923. Serial No. 627,679.

Our invention relates to sand blast machines, and particularly to machines of the self-contained type, in which the sand or like abrasive material is automatically recovered and returned to the blast mechanism during the operation of the barrel.

Among the objects of our invention may be mentioned—

(1) Improved ventilation of the barrel in order to maintain the blast sand clean and in condition for its most efficient use;

(2) Greater facility in loading and discharging the barrel;

(3) Improved means for effecting the recovery and re-use of the sand;

(4) A construction and assembly of the constituent elements of the machine which facilitates assembly, repair and replacement of parts;

(5) Other features of improvement hereinafter described or shown in the accompanying drawings in which—

Fig. 1 is a front end elevation of a machine which embodies our invention in one form;

Fig. 2 is a vertical section on the line 2—2, Fig. 1;

Fig. 3 is a vertical section through one of the blast nozzles;

Fig. 4 is a horizontal section through the blast end of the machine; and

Fig. 5 is a broken end elevation of the same.

The present apparatus possesses various structural and operating advantages over its prototypes illustrated in the patent to Dreisbach No. 948,271, February 1, 1910, and the copending application of C. E. Billings filed herewith.

The barrel proper comprises a frusto-conical rotary body 6 of relatively heavy weight sheet metal, for the reception of the castings which it is desired to clean by the sand blast. As here shown, the body 6 is provided on its

inner face with tumbling cleats 6^a and is perforated to form a screen, for the purpose hereinafter explained. It is clamped between the rotary heads 7 and 8 at opposite ends thereof by longitudinally extending tie bolts 9 exterior to the screen body. Flanges or lugs 10 and 11 on the respective heads, position and center the screen with respect thereto. The exposed nuts 12 at the charging end of the barrel permit their

ready attachment and detachment for assembling and dis-assembling the barrel structure.

Surrounding and spaced from the screen is an outer, relatively light sheet metal shell 13, secured to the heads 7 and 8 and rotating therewith. In the annular space 14 between the screen and shell, one or more spiral ribs 15 are arranged, which serve to automatically convey to one end of the barrel the sand which falls through the screen after playing upon the castings. The spiral 15 is apertured or slotted at predetermined points to accommodate the tie bolts 9 which pass therethrough. As shown in the drawings, the rib 15 reaches from the shell 13 to the screen 6. As a matter of practical construction it is preferred to leave a slight clearance between the rib and screen, since assembly of the parts is thus facilitated. In either case, however, the rib is secured in position by screws passing through the shell 13 and taking into lugs or flanges 15^a offset from the outer margin of the rib.

At the charging and discharging end of the barrel, a closure diaphragm 16 is provided. In order to permit ready access to the interior of the barrel, this diaphragm is made independent of the head 7 and comprises a semi-circular closure area, integral with a ring 17 by which it is secured, as by cap screws 18, to the head 7. A cooperating semi-circular door 19 is hinged at 20 to the diaphragm 16 and completes the removable closure at this end of the barrel. The door carries latches 21 of any suitable type cooperating with keepers 22 secured to the head 7 and serving to hold the door shut during the operation of the barrel. Locking devices, not shown, may be provided to hold the latches in engaging position. A latch 23 on the opposite side of the head 7 serves to hold the door open during the discharge of the barrel.

Both diaphragm and door on their inner faces are provided with renewable lining plates 24 spaced away by studs tapped to receive the securing screws 25. The door is pierced by ventilation holes 26, to permit a draft through the blast chamber to carry off dust. The spacing of the lining plate from the door permits the escape of the draft around the free margins of the plate—while at the same time preventing

the blast sand from being ejected through the holes 26.

At the opposite end of the chamber, the head 8 is integral with the closure diaphragm 27 which is also preferably perforated at 28 for ventilation purposes. It is centrally apertured at 29 to accommodate the blast nozzles 30. A guard 31 of any suitable sort, which may be detachably secured in any way 10 to the nozzles, prevents the castings from entering the aperture 29.

At appropriate points, preferably arranged radially outside the points of attachment of the tie bolts 9, the head 8 has 15 openings 32 formed therein to permit the sand, returned by the spiral rib 15, to pass through the head to the elevator scoops 33. The latter are carried by or are integral with the head 8, and are here shown as 20 webs extending between the latter and the spaced flange 34—which with the head, constitute a rotary elevator drum with peripheral buckets.

The heads 7 and 8 have peripheral bearing rims 35 and 36 which rest upon pairs 25 of rollers 37 and 38, driven in any suitable manner to rotate the barrel during its operation. As here shown, the rollers are mounted on spindles 39 and 40 journaled 30 in a stationary base frame 41 supported in pedestals 42. Bevel gears 43 on the spindle are driven by bevel pinions 44 on a cross shaft 45 carrying fast and loose pulleys 46—47 respectively.

35 Brackets 48 bolted to the base frame carry a stationary semi-circular closure plate 49, and in turn support a second set of brackets 50 carrying a complementary semi-circular closure plate 51 which, with its associated 40 parts, completes the closure of the outer end of the elevator drum. Into this closed drum opens the suction pipe 52 leading to a draft fan (not shown) which creates a suction through the barrel sufficient not only to 45 carry off the air introduced by the blast nozzles 30, but also to create a draft through the barrel which removes dust.

50 Mounted on the bracket 50 is the hopper 53 to which the recuperated sand is delivered by the elevator buckets, and from which the sand is admitted through slide valves 54 to the blast nozzles 30 supported beneath the hopper. Different angular inclinations are imparted to the nozzles to cover different 55 portions of the charge within the screen.

The nozzle construction is indicated in Fig. 3. The sand descends from the hopper through a throat 55 into a mixing chamber 56, to which opens on one side the air pipe 57 aligned with the nozzle 30 of greater internal diameter on the other side. The nozzle is preferably detachably held in place by a screw bushing 58 passed over the nozzle and holding its head 59 to a conical seat 65 in the wall of the mixing chamber. The

latter is preferably of spherical internal contour and of sufficient size to accommodate a quantity of sand in excess of that delivered through the nozzle. The excess sand forms a lining for the chamber which prevents injurious scouring of the walls by the sand under the influence of the blast, as well as affording a sand reserve which insures a steady blast action regardless of temporary variations in the feed from the hopper 53. 75

The operation of the apparatus is as follows: When the barrel is to be charged, it is preferably brought to the position shown in Figs. 1 and 2, the latches 21 released and the door 19 swung down. The castings or 80 the like are then charged into the screen 6 through the door opening, and the door swung up and secured in closed position. The driving belt is now shifted to the fast pulley 46 and the barrel thus set in motion. 85 The suction fan is started, the blast is admitted to the nozzles, and the sand valves 54 opened, so that the sand blast plays upon the castings as they are tumbled in the rotating drum. 90

As the sand filters down through the charge it escapes through the holes in the screen 6 and enters the annular chamber 14 between the screen and the shell 13. The direction of rotation of the barrel is such 95 that the spiral rib 15 forces this spent sand toward the head 8 through which it escapes, by ports 32, to the elevator buckets 33. By these it is lifted and returned to the hopper 53, from which it feeds again to the blast nozzles. 100

The exhaust fan exerting suction through the draft pipe 52 carries off the dust which results from the blast operation and thus not only keeps the sand clean but prevents 105 contamination of the surrounding air. 105

When the castings have been sufficiently treated, the blast is cut off and the barrel halted—preferably with the door 19 in the “up” position illustrated. It may then be 110 unlatched, swung down, secured open by the latch 23, and the barrel rotated. As the door opening moves downward, the castings fall out and may be received in a wheelbarrow or other receptacle for removal. The 115 inclination of the barrel wall toward the door renders the automatic discharge of the barrel practically complete. In any event it facilitates the removal of any castings which may remain within, and if rotation is 120 continued, complete evacuation of the charge may be thus obtained. 120

Access to the interior of the barrel is readily effected without dismounting, by removal of the closure diaphragm 16 and door 19 by 125 unscrewing the cap screws 18. To replace the barrel body 6, it is merely necessary to remove the nuts 12 from the tie bolts 9 and the cap screws which hold the shell 13 to the head 7, whereupon the latter may be re- 130

removed and the new barrel body placed in position. The plates 24 at the front of the barrel, which are perhaps the most subject to wear, may be replaced without any disassembly, since the door opening is sufficiently large to admit a workman to the entrance of the barrel for replacement of the blast nozzles when this is necessary. The same is true with respect to the nozzles, since the door opening is of sufficient size to permit a workman to enter the barrel, or to reach into the barrel, remove the guard 31, and detach the nozzle securing bushings 58.

Various modifications in details of construction and arrangement of parts will readily occur to those skilled in the art, which do not depart from what we claim as our invention.

We claim—

20 1. In a rotary sand blast barrel, a frusto-conical barrel body, heads at opposite ends of the body, and a charging and discharging door opening at the end of greater diameter, in combination with sand blast means at the opposite end of the body.

2. A rotary blast barrel comprising a rotary shell, a frusto-conical perforated body arranged within and rotating with the shell, a closure member for the body and shell elements at the end of greater diameter of the frusto-conical body, said end closure comprising a semi-circular member rigid with the frusto-conical body member, a second semicircular door complementary to said fixed member and completing the closure, hinge means for supporting the pivoted portion of the closure upon the fixed portion thereof, latching means for holding said pivoted portion in closure position, and sup-

plementary latching means for holding said pivoted portion in fully open position. 40

3. In a rotary sand blast apparatus, a perforated body for containing a charge, a surrounding shell spaced therefrom, rotary heads between which said body and shell extend, a spiral conveyor arranged in the interspace between the body and shell, and tie bolts passing through said spiral and engaging said heads to clamp the body and shell therebetween. 45

4. In a rotary sand blast apparatus, a perforated body member, a shell surrounding but spaced therefrom, heads at opposite ends of said body and tie bolts extending between said heads and arranged in the interspace between the body and shell, a spiral rib arranged in said interspace for conveying to one end of the barrel the sand passing through the perforated body, the head at the end to which said spiral delivers being apertured at a point located radially outside the point of attachment of the bolt. 50

5. In a rotary sand blast barrel, a frusto-conical perforated barrel body, a cylindrical shell surrounding but spaced therefrom, rotary heads at opposite ends of and common to said frusto-conical barrel body and shell, the ends of which bear against the opposed faces of said heads, together with tie bolts extending between said heads and located between the shell and frusto conical body and serving to unite the said parts into a rigid barrel unit. 55

In testimony whereof we have signed our names to this specification.

GEORGE C. FATSCHER.
CLARENCE E. BILLINGS.
